UNITED STATES PATENT OFFICE

122,932

DESIGN FOR A GLIDER END FRAME

William I. Smith, Goshen, Ind., assignor to The Hettrick Manufacturing Company, Toledo, Ohio, a corporation of Ohio

Application July 8, 1940, Serial No. 93,490

Term of patent 14 years

To all whom it may concern:

Be it known that I, William I. Smith, a citizen of the United States and resident of Goshen, Elkhart County, Indiana, have invented a new, original, and ornamental Design for a Glider End Frame, of which the following is a specification, reference being had to the accompanying drawing forming a part thereof.

In the drawing:

Figure 1 is a front perspective view of the glider end frame, showing my new design;

Figure 2 is a perspective view of the rear of the glider end frame; and

Figure 3 is an enlarged transverse sectional view on the line 3—3 of Figure 1.

I claim:

The ornamental design for a glider end frame, as shown.

WILLIAM I. SMITH.
